(57) **CLAIM**

The ornamental design for a drawer with adjustable shelf, as shown and described.

DESCRIPTION

FIG. 1 is a perspective view of a drawer with adjustable shelf according to our new ornamental design, with the shelf on a horizontal orientation;

FIG. 2 is a cross section along lines 2-2 of FIG. 1;

FIG. 3 is another perspective view of the drawer with adjustable shelf shown in FIG. 1, but with the shelf in a vertical orientation;

FIG. 4 is a cross section taken along lines 4-4 of FIG. 3;

FIG. 5 is a perspective view of the shelf, shown separately for completeness of illustration;

FIG. 6 is a top view thereof, with the bottom view being a mirror image thereof;

FIG. 7 is a front view thereof, with the rear view being a mirror image thereof; and,

FIG. 8 is a left side view thereof; with the right side view being a mirror image thereof.

The bottom of the drawer is unornamented and forms no part of the claimed design.

The broken lines immediately adjacent to the shaded areas represent the bounds of the claimed design while all other broken lines shown in the drawings illustrate environmental structure; the broken lines form no part of the claimed design.
